UNITED STATES PATENT OFFICE.

HARRISON I. COLE, OF SOUTH WEYMOUTH, MASSACHUSETTS.

TRAWL-TOWING BLOCK.

1,086,893.

Specification of Letters Patent.

Patented Feb. 10, 1914.

Application filed October 27, 1913. Serial No. 797,465.

To all whom it may concern:

Be it known that I, HARRISON I. COLE, a citizen of the United States, residing at South Weymouth, in the county of Norfolk 5 and State of Massachusetts, have invented certain new and useful Improvements in Trawl-Towing Blocks, of which the following is a specification, reference being had to the accompanying drawings, forming 10 part thereof.

This invention has reference to improvements in blocks particularly adapted for use in sustaining trawl towing cables.

One object of the invention is to so construct a trawl towing block, so called, that the towing cables readily may be placed in position therein and that the sustaining wearing member for said cables may space a pair of pivoted arms or links whereby the 20 construction of the block is simplified.

Other objects of the invention will appear from the following description.

The invention consists in the novel construction of the trawl towing block as shall 25 hereinafter be more fully described and pointed out in the claims.

Figure 1, represents a front view of the improved block, a portion of a cable being indicated in position therein. Fig. 2, represents a side view of the same, the position of the wearing block and its sustaining links when open to receive the towing cables being indicated. Fig. 3, represents a sectional view of portions of the wearing block and 35 its sustaining links as taken on line 3—3 Fig. 2. Fig. 4, represents a sectional view as taken on line 4—4 Fig. 1.

Similar characters of reference designate corresponding parts throughout.

40 Trawl towing blocks of the nature herein referred to are used for sustaining one or more towing cables, usually two, at a point between the point at which said cables are connected with the towing machinery of 45 a vessel and the trawls. In ordinary use the trawl towing block is engaged with the cables after such cables are paid out to some extent and hence provision is made to open and close one arm of the block to permit 50 the swinging downward of the cable sustaining and wearing member. Thus the location of the cables in the towing block is facilitated. It is also of importance that the 55 wearing member, on which the cables ride, should be removable and it is desirable that such wearing member be so constructed and

combined with the swinging arms or links of the towing block that said links may readily swing on their pivots.

In carrying this invention into practice I 60 construct a trawl towing block or frame having the main arm 5 having near its upper end the projection 6 which is transversely perforated to receive the pin 7. The lower end of arm 5 is transversely perforated to receive the bolt 8 on which the pair of links or plates 9, 9 are pivoted while the other ends of said links 9, 9 are pivotally mounted on the bolt 10 of the closure arm 11 having the loop 70 or member 12 the opening of which is adapted to receive the projection 6. The cable sustaining or wearing block or member has the head or saddle 13 of a size to be received between the arms 5 and 11 and of a width 75 to bear on the upper edges of the links 9, 9 and from said head 13 extends the contracted portion or spacing neck 14 located between the links 9, 9 and spacing said links apart from the arms 5 and 11 so that said 80 links may swing freely on the bolts 8 and 10. The lower end 15 of said wearing member is wider than its neck 14 to engage the lower edges of said links 9, 9.

In operation to place the cables A, A, in 85 position as shown in Figs. 1 and 2 the pin 7 is withdrawn from its perforation in projection 6 and the arm 11 is swung down until said arm and the links 9, 9 extend downward as indicated in Fig. 2. One or more of the 90 cables A, A are then drawn approximately into the position shown in Fig. 2 and the arm 11 and links 9, 9 with the wearing member are then swung upward until the loop 12 of arm 11 is engaged with projection 6 of 95 arm 5 and the saddle or head 13 of said wearing member receives the cables A, A. The pin 7 is then inserted in its perforation in projection 6 to prevent the swinging of the loop end of said arm 11 in the opening 100 direction. When the saddle 13 of the spacing member becomes unduly worn, by the riding thereon of the cables, one of the bolts 8 or 10 may be removed thus permitting the freed ends of links 9, 9 to swing clear of the 105 arm 5 or 11, as the case may be, whereby the worn spacing member may slide from between said links 9, 9 and a new spacing member may be substituted therefor after which the ends of said links 9, 9 may again 110 be secured on their bolt.

At the upper end of arm 5, in Fig. 2 is

indicated by dotted lines a shackle of any usual and well known construction by means of which the towing block may be secured to any well known sustaining device but said shackle forms no part of the present invention.

Having thus described my invention I claim as new and desire to secure by Letters Patent.

10. 1. A trawl towing block of the nature described comprising a main arm having at one end a transverse bolt, a pair of links pivotally mounted on said bolt, a closure arm having a bolt on which said links are 15 also pivoted, and a wearing member located between said links and spacing them apart free from said arms, said arms having complementary engaging means.

20. 2. A trawl towing block of the nature described comprising a main arm having a

rigid projection near its upper end and a transverse perforation at its lower end, a bolt extending through said perforation, a pair of links perforated near their ends pivotally mounted on said bolt, a second bolt 25 extending through the perforations in said links, a closure arm pivotally mounted on said second bolt and having an opening to receive said projection of said main arm, a spacing member located between said links 30 to space them apart free from said arms and having a saddle extending over the upper edges of said links, and a pin adapted to be secured in said projection of said main arm for holding said closure arm in position. 35
